UNITED STATES PATENT OFFICE.

JAMES F. WINCHELL, OF SPRINGFIELD, OHIO, ASSIGNOR TO THE FOOS MANUFACTURING COMPANY, OF SAME PLACE.

GRINDING AND CRUSHING MILL.

SPECIFICATION forming part of Letters Patent No. 408,781, dated August 13, 1889.

Application filed September 17, 1887. Serial No. 249,951. (No model.)

To all whom it may concern:

Be it known that I, JAMES F. WINCHELL, a citizen of the United States, residing at Springfield, in the county of Clark and State of Ohio, 5 have invented certain new and useful Improvements in Grinding and Crushing Mills, of which the following is a specification, reference being had therein to the accompanying drawings.

10 This invention relates to improvements in crushing and grinding mills, and is designed as an improvement upon the crushing and grinding mill upon which I filed application for Letters Patent on the 11th day of August, 1887, Serial No. 246,685.

15 The present objects which I have in view are, first, that of increasing and decreasing the space through which the material—particularly corn-cobs and other large substances—passes between the feeding-crushers to a greater extent by a given movement of the cut-off, which is in the hopper above them, than is the case by a like movement of the cut-off in the application above alluded to, 20 this being accomplished by tapering the said feeding-crushers; secondly, that of providing an opening through which the material—particularly cereals—will pass downward through the cut-off in such manner that, while they 25 descend freely, they will yet not descend in too large a quantity for the capacity of the other mechanism of the mill at the speeds at which it is convenient to drive it, this being accomplished by having an opening through 30 the cut-off proper and a supplemental cut-off to control the size of this opening when the cut-off proper is in closed position, both of which objects will be hereinafter more fully explained, as also the mechanism by which 35 they are accomplished.

40 In the accompanying drawings, forming a part of this specification, and on which like reference-letters indicate corresponding parts, Figure 1 represents a vertical sectional view 45 of the mill, showing some of the parts in side elevation; Fig. 2, an enlarged plan view of the hopper, the cut-offs, the feeding-crushers, the agitator, and the operating-gears; Fig. 3, a plan view of the cut-off proper and the supplemental cut-off; Fig. 4, a similar view to Fig.

2 with the cut-offs removed and one of the intergearing pinions dispensed with; Fig. 5, a transverse sectional view of the cut-offs on the line $x-x$ of Fig. 3; Fig. 6, a like view of the cut-off proper on the line $y-y$ of Fig. 3 and an 55 end view of the supplemental cut-off; Fig. 7, an end view of the cut-off, and Fig. 8 a modification of the feeding-crushers in plan.

The letter A designates a mill constructed substantially in accordance with the machine 60 illustrated in Letters Patent granted to me March 15, 1887, No. 359,588, for crushing and grinding mills. On the main shaft B of the mill and within the chamber C is a crushing-conveyer D, which may be of the form shown— 65 that is to say, may consist of a cylindrical body with crushing and conveying lugs formed thereon, or may be of the character shown and described in said Letters Patent, and which acts upon the material in the manner 70 and for the purposes set forth in said patent, with this difference—namely, that when constructed with lugs, substantially as shown, it will convey the material to the grinding mechanism irrespective of the direction in which 75 it is rotated.

The letter F designates that portion of the mill-casing which stands above the chamber C and upon which the hopper G rests. Mounted at a convenient point above the crushing-conveyer—as, for instance, in the lower part 80 of the hopper G—are two feeding-crushers H and I, having each a number of protuberances J, which act to draw the material between the crushers and crush and partially 85 reduce the material as it is fed to the crushing-conveyer below.

The arrangement of the protuberances J upon the feeding-crushers may be left to the choice of the manufacturer or to the exigencies incident to the particular material designed to be acted upon, but may be arranged as hereinafter explained. These feeding-crushers are of tapering form—that is to say, the space between their peripheries at one 90 end is less than the space at the other end, and the end where the space is least is preferably that which is over, or from which the material descends to, the end of the feeding-crusher farthest from the grinding mechan- 95 100

ism, whereby the material, when passing between the feeding-crushers at said end, (the end mostly used,) is afterward acted upon by the whole or a greater part of the length of 5 the crushing-conveyer, which latter action, while not necessary, is yet an advantage. The degree of the taper of the feeding-crushers may vary; yet that shown is the preferred degree of divergence between them.

10 The letter K refers to the cut-off proper, which is mounted in the hopper in substantially the same manner as the cut-off in the application already referred to, and, like that cut-off, preferably consists of a plate of cast- 15 iron, and is held in any adjusted position by the same or any suitable fastening device, as at L. In the present case, however, this cut-off is preferably located between the feeding-crushers and the agitator presently to be 20 referred to, so that it may be placed against the wall of the hopper under the agitator and cut off the passage of material to the feeding-crushers, except through the opening M in the cut-off. (See Fig. 3.) The supplemental 25 cut-off N controls the size of this opening, which is used particularly for feeding small material, as cereals, to the lower mechanism. It is in feeding such material that the agitator is particularly used, though it may be 30 used when larger material, as corn-cobs, is being fed. I have found in actual practice that if the cut-off proper, which extends across the entire hopper, is drawn out sufficiently to form an opening between its inner end and 35 the opposite wall of the hopper large enough for the free descent of the small material, as cereals, the amount of such material which will pass through such an opening will be in excess of the capacity of the remaining mech- 40 anism of the mill to grind, &c., at the speeds at which such mechanism is ordinarily operated. On the other hand, I have found that if said opening be small enough to admit the proper supply it is so small that such material 45 will not readily feed with regularity. With the opening as at M, it is so proportioned that when there is width enough between the end of the supplemental cut-off and the wall of the hopper for the material 50 to feed properly, there is still not length enough in the opening to allow too much material to pass through. These things I have ascertained in the practical use of the mill. I prefer to place the supplemental cut-off at 55 an angle, as shown, so as to run clear of the fastening device L, and I also prefer to rabbet the upper surface of the cut-off proper to receive the supplemental cut-off, as shown in Fig. 5. Along the under edges of the opening M the cut-off K is also rabbeted and the cut-off N provided with the plate O, which fits in the said rabbet and prevents the cut-off N from working upward. A slot and set-screw P form a convenient means to hold the cut- 60 off N in any adjusted position.

The letter Q refers to the rotating agitator, and the letter R to its pinion. These are of

the character also shown and described in said application.

I will now refer to the mechanism for actuating the feeding-crushers and the agitator. This may be largely varied; but that shown is preferred. It consists of the gear-wheel S, mounted on one of the feeding-crushers and meshing with a pinion T on the main shaft. 75 This wheel is transferable from one crusher to the other, so as to operate them toward each other no matter in which direction the main shaft is rotating, the crushers themselves being intergeared by pinions U and V, the former being preferably somewhat larger than the latter, so as to mesh with the pinion R of the agitator. By these means it will be observed that the feeding-crushers are rotated with a certain relation with respect to the 80 speed of the crushing-conveyer, whereby the material is properly reduced by the feeding-crushers and said crushing-conveyer before it reaches the grinding mechanism and is also properly fed thereto. In Fig. 4 I have illustrated one feeding-crusher without a pinion, and which therefore would act principally as a revoluble surface against which the other crusher would operate upon the material. The pinion and gear-wheel may be placed 85 upon either of the crushers, according to choice or the direction the main shaft is rotated in. I have shown dotted lines in this figure to illustrate that the crushers may be parallel, if desired, in the instance in which 90 one of them is inactive, while the other, by a suitable intermediate mechanism, is operatively connected with the crushing-conveyer.

I have hereinbefore referred to arranging the protuberances J. This may be done as 105 more clearly seen in Figs. 4 and 8, in the latter of which the feeding-crushers are parallel. The protuberances of the respective crushers grow shorter and shorter from one end (in Fig. 8 the end corresponding to the smaller 110 end of the tapering crushers) to the other end. In Fig. 4 they are opposite each other, while in Fig. 8 they lap each other less and less for a distance and then terminate farther and farther from each other the remaining distance. Either arrangement causes the feeding-crushers to draw less and less of the material between them at one end than at and toward the other end, because short protuberances do not engage as much material as 115 longer ones.

The range of difference is greater in the instance of the tapering feeding-crushers than in those that are parallel, because in the former the protuberances are longer, as measured from the periphery of the roller portion of the crushers, than in the latter when similarly measured, and also, to some extent at least, because the space between the tapering form is greater as the protuberances grow 125 longer than in the parallel form. The arrangement of the protuberances round or on the respective crushers may be either spiral or in parallel lines, or, indeed, may be irregu- 130

lar; but in any instance the crushers are so geared together as that the protuberances of one crusher properly coact, in view of the particular arrangement, with those of the other 5 in the reduction and feeding of the material.

It will be noticed in Fig. 7 that the inner end of the cut-off proper depends in two plates *a a*, the outer edges of which agree with the incline of the hopper and the inner edges 10 agree with the sweep of the protuberance. The purpose of these plates is to prevent the material from getting between the under side of the cut-off proper and the feeding-crushers.

As already observed, I do not confine myself to the means shown for transmitting motion from the main shaft to the feeding-crushers, as belts and pulleys, sprocket-wheels and drive-chains, or friction-pulleys, &c., may be used instead of the gear-wheel and pinion 15 shown.

Having thus fully described my invention, what I claim as new, and desire to secure by Letters Patent, is—

1. In a mill, the combination, with that portion into which the material is fed, of inter-gearing tapering crushers mounted therein with their axes substantially parallel, whereby a gradually-increasing space is formed between their bodies from one end to the other, 25 30 projections extending from the crushers, and means to actuate the crushers.

2. In a mill, the combination, with that portion into which the material is fed and tapering crushers mounted therein with their axes 35 substantially parallel, whereby a gradually-increasing space is formed between them from end to end, projections extending from the crushers, and means to rotate the crushers, of an adjustable cut-off mounted above the crushers and approximately thereto and arranged 40 to be moved back and forth over the said space.

3. In a mill, the following instrumentalities: a hopper and tapering crushers mounted therein with their axes substantially parallel, whereby the space between them widens from one end toward the other, projections extending from the crushers, and means to rotate the crushers, an adjustable cut-off mounted above the crushers in proximity thereto and arranged to be moved back and forth and over the said space, an opening in the cut-off, a supplemental cut-off to control the size of said opening, an agitator arranged to feed the material through the said opening, and means to actuate the agitator. 45 50 55

4. In a mill, the combination, with the hopper into which the material is fed, of two tapering feeding-crushers mounted therein with their axes parallel and having protuberances 60 extending therefrom which grow shorter and shorter from one end toward the other, for the purpose set forth.

5. In a mill, the combination, with a cut-off proper having a feed-opening therein and a supplemental cut-off fitted thereto and arranged to open and close said feed-opening, of an agitator mounted above said cut-offs and arranged to feed the material to said opening. 65 70

6. In a mill, the combination, with the portion into which the material is primarily fed and two independent disconnected crushers mounted therein, of a main shaft, a crushing-conveyer, grinding mechanism, and an intermediate operating mechanism interchangeable from one crusher to the other and arranged to receive motion from the said main shaft. 75

In testimony whereof I affix my signature in presence of two witnesses.

JAMES F. WINCHELL.
